(57) CLAIM

The ornamental design for a plant container, as shown and described.

DESCRIPTION

FIG. 1 is a perspective view of a plant container showing my new design.

FIG. 2 is a rear perspective view thereof.

FIG. 3 is a side view thereof.

FIG. 4 is a front perspective view thereof; and,

FIG. 5 is a cross-sectional view thereof taken along line 5-5 in FIG. 4.

The broken lines in the figures depict portions of the plant container that form no part of the claimed design.
